UNITED STATES PATENT OFFICE

AXEL H. PEARSON, OF CERESCO, NEBRASKA

AUTOMATIC FIRE ALARM

Application filed July 6, 1929. Serial No. 376,444.

This invention relates to automatic fire alarm devices and has for its primary object the provision of certain novel and useful improvements in systems of this type, the invention being characterized by a novel arrangement and construction of parts, which render the system simple in construction and operation, thoroughly reliable, practical, strong, durable, and well adapted for the purpose designed. The invention consists in the provision of a sound emitting device arranged in circuit with a plurality of switches, each of the switches being normally held open through the medium of suitable heat affected devices, whereby upon an outbreak of fire, either the flames from the fire or the heat radiated therefrom will destroy the means maintaining the switches in open position, thus permitting a closing of the switch or switches to permit an operation of the sounding device whereby one may be quickly warned of the situation.

Other objects and advantages of this invention, will become more apparent to the reader during a study of the following description, taken in connection with the accompanying drawings, wherein:

Figure 1 is a side elevation of a device embodying this invention, the casing for containing and protecting the source of electrical supply being broken away.

Figure 2 is a side elevation of a switch mechanism constructed in accordance with this invention, the switch being shown in an open position.

Figure 3 is a top plan view thereof.

Figure 4 is a vertical transverse sectional view taken substantially on line 4-4 of Figure 2.

Figure 5 is a diagrammatic view of the system showing the same installed in a dwelling.

Figure 6 is a view similar to Figure 4 and taken on line 6-6 of Figure 2, looking in the direction of the arrows.

With reference more in detail to the drawings, it will be seen that the invention contemplates the provision of a suitable, substantially rectangular casing 5, which is open at one end. A closure or cover 6 fits down

over the casing for closing the open end of the casing. Located adjacent the casing 5 is a suitable source of electrical energy such as herein designated, comprising a plurality of dry cell batteries 7 in suitable circuit one 55 with another, the number of batteries being of course variable, to suit conditions.

One end wall of the housing is provided with a suitable opening 8 and disposed opposite to the opening for substantially closing the same is a plate 9 of mica or suitable similar material which mica is disposed with a suitable frame 10 which is bolted or otherwise secured to the end wall of the housing.

A clear knowledge of this frame will be 65 best gleaned when attention is directed to one side wall of the housing 5, wherein there is provided a second opening which is also enclosed with a plate of mica 9' located within a frame 10' surrounding the opening 70 for maintaining the mica plate 9 in closed position with respect to the opening, and it will be seen that this frame 10' is provided with diametrically opposed apertured ears 75 for the reception of suitable bolts, screws or other fastening elements 11, whereby the same may be secured in position about the opening.

In this connection it is to be mentioned that the frame 10 is in every way similar to 80 the frame 10'. Located adjacent this opening and secured to the housing 5 on the same side wall of the housing is a suitable horn structure designated generally by the reference character 12. The horn structure 12 85 is fixed in position to the side of the housing 5 through the medium of suitable supporting bracket 13. Located within the housing 14 of the horn a suitable electric motor is disposed for actuating the horn. 90 The structure of the horn 12 and its motor 14 is conventional and a detailed description thereof is deemed unnecessary.

A suitable electric conduit wire 15 to be 95 connected to a suitable switch mechanism designated generally by the reference character 16, which mechanism 16 will be herein-after more fully described. A negative conduit wire 17 leads from the battery on the other end and has suitable connection as at 100

18 to the motor within the casing 14 of the horn 12.

Attention is now directed to my switch mechanism, wherein it is to be noted that the same consists of a substantially rectangular frame 18. A fork 19 has its legs 20-20 located within the frame 18 and a pivot shaft or rod 21 has its opposite ends extending through the side members of the frame 18 adjacent one end of the frame. The extremities of the legs 20-20 of the fork member 19 are also suitably apertured so as to receive a pivot pin 21.

Adjacent their opposite ends the legs 20-20 of the fork 19 converge inwardly towards one another to determinate in spaced parallel extensions 22-22. An elongated copper plate 23 of a length substantially equal to the length of the fork 19 extends longitudinally of the fork and one end of this plate 23 is connected to an intermediate position of the pivot pin 21 while the opposite end portion of the plate 23 extends between the extensions 22-22 of the fork as clearly shown in Figure 3. Suitable clamping bolts 24 pass through the extensions 22-22 and that portion of the plate 23 clamps therebetween for holding the said extensions and plate 23 in clamped relation.

As shown to advantage of Figure 2, that portion of the plate between the extensions 22-22 is extended downwardly at its lower edge as at 23'. The purpose of this will be hereinafter more fully disclosed. To an intermediate portion of each of the legs 20 of the fork 19 there is pivotally connected a guide bore 24, said guide bore being longitudinally slotted as at 24'. A stud or pin 26 extends laterally from the outer face of each of the side members of the frame 18, and the pin is receivable in the slot 25 of the guide pin. Thus it will be seen that this pin and slot connection will act as a stop when the fork member 19 is moved upwardly upon its pivotal connection.

A substantially U-shaped bracket plate 27 is located within the frame 18 adjacent one end of the frame and this bracket plate 27 has its legs bolted or otherwise secured as at 28 to the end member of the frame 18 as clearly suggested in Figure 3. The purpose of the bracket plate 27 will be also herein-after more fully set forth. At this last mentioned end of the frame 18 I provide a plurality of layers 29 of mica, the layers being disposed side by side as clearly shown. The innermost layer is disposed against the outer face of the end member of the frame 18, and a contact plate 30 is disposed against the outermost of these layers 29.

As shown to advantage in Figure 6, this contact plate 30 extends upwardly beyond the top edge of the layers 29, and upon its lower edge the contact plate has a reduced extension 31 which terminates substantially

even with the lower edges of the layers. Additional layers 29', also of mica, are disposed on the opposite face of the contact plate 30 and to the outermost face of the outer layer 29' I propose to place a suitable plate 32. 70 Bolts or rivets 33 extend through the plate 32, the layers 29', the layers 29 and also through the end member of the frame 18, as shown in Figure 3. These bolts extend on opposite sides of the extension 31 of the plate 30 so as to be out of contact with this plate, and at the same time securely clamp the plate 30 between the layers 29 and 29', the entire arrangement being neat and compact as shown. 80

Obviously the plate 30 constitutes the stationary contact of the switch, while the plate 23 constitutes the movable contact of the switch, which is designated generally by the reference character 16. For normally maintaining the movable contact 23 out of engagement with the stationary contact, I provide a suitable block 34 of celluloid or other similar heat affected material, said block 34 being located between the legs of the U-shaped plate 27 in spaced relation with the ground portion of the plate through the medium of suitable screws 35 which are threaded in spaced relation through the ground portion of the plate 27 and the lower portion of the block 34 as clearly shown in Figure 3. The block 34 extends upwardly beyond the top edge of the stationary contact plate 30 so that the extending portion 23' of the movable contact 23 may rest on the top edge of this plate 34 and stationary contact 30. 95

The fork member 19 is consequently disposed in that position shown in Figure 2. It is yet to be mentioned that at the free ends of the extensions 22 of the fork 19 there is suitably secured weights 36, there being one weight to each of the said extensions. Obviously the weights 36 will aid in urging the fork 19 downwardly so that the extension 23 of the plate 23 may as it were cut its way through the celluloid 34 when the same has become affected by heat so as to begin its melting and in this way hastening the closing of the switch 16. 105

At one vertical edge thereof the plate 30 is provided with an extension 30' which is suitably apertured for the reception of a set screw 37 so that a suitable conductor may have one end thereof connected thereto the opposite end of the conductor, not shown, being suitably connected in circuit with the motor within the housing 14 of the horn 12, as is apparent. 115

The frame 18 of the switch 16 has one side member thereof provided with a suitable bracket 38, and bolts 39 extend through suitable openings formed in the plate and through that side wall of the housing 5 to which the horn 12 is attached, as clearly shown in Figure 1. 125 130

As shown diagrammatically in Figure 5, in the application of my device the battery containing casing 5, the horn 12, and switch 16 secured to one side thereof is as a unit located in one room of the dwelling, herein the dwelling being designated generally by the reference character A. Located within the separate room of the dwelling or in the basement, first floor, second floor, and in the chimney of the dwelling, one within each room are located a switch 16', all of which switches 16' are constructed in every way similar to the switch 16 as herein just described.

15 A conductor 41 leads from the motor of the horn 12 to one of the switches 16 while the positive conductor 15 leads from a battery 7 on the other end of the series of batteries to the negative side of the said one switch 16'. The remaining switches 16' are in circuit with the positive and negative conductors 15 and 41 respectively as diagrammatically shown in Figure 5. The conductor 15' leads from the positive wire 15 and is connected as at 42 to the movable contact plate 23 adjacent the pivoted end portion of the plate as shown in Figure 3. A suitable connector wire 43 will of course have one end fixed to the stationary contact 30 through the medium of the ear 30' being connected thereto through the medium of the set screw 37, said conductor 43 being a branch of the conductor 41, which conductor 41 is connected in circuit with the motor of the horn 12.

20 Obviously then, actuation of any of the switches 16' to assume a closed position will of course close the circuit from the battery 7 to the motor of the horn, whereby the horn will be sounded. Occupants of the dwelling, or those nearby will be quickly warned of fire.

25 The switch 16 and switches 16' are maintained in an open position or that position shown in Figure 2 with regard to switch 16. Of course, when fire breaks out, the temperature of the room in which either of the switches may be located becomes such as to melt the celluloid 34, the pressure of the weights 36 upon the fork 19 will of course cause a downward movement of the fork on its pivotal connection to permit the movable contact 23 to engage with the stationary contact 30 to close the circuit between the batteries and the motor of the horn upon which the horn is then sounded for a purpose obvious.

30 It is important that at least one switch, such as the switch 16, be secured to the casing 5 which contains the batteries 7, in this manner protecting the batteries and the horn 12 since obviously the celluloid 34 will melt to permit a closing of the switch before damage can be done to the batteries or to the horn.

35 If however, the switches were scattered throughout the house, and all of the said

switches remote from the casing 5 and horn 12 obviously if the fire would enter the casing where the horn is located damage would of course be done to the batteries and the horn before one of the switches could be put into 70 operation thus of course rendering the device useless and incapable of performing the function intended. However, in assembling the source of electrical energy, the switch mechanism and the horn all in a compact structure or single unit as shown, eliminating such danger and the device is at all times capable of operating under the conditions stated. 75

From the foregoing, it will be seen that I have provided an automatic alarm device for 80 fires which will at all times be positive in operation, is strong, durable, simple in construction, yet thoroughly reliable, practical and efficient in use.

Even though I have herein shown and described the preferred embodiment of my invention, it is to be understood that the same is susceptible to changes fully comprehended by the spirit of the invention and the scope of the appended claims. 85

Having thus described my invention, what I wish to claim is:

1. A switch adapted to be arranged in a signal circuit and comprising a frame, an attaching plate carried by the frame, a contact member fixed to the frame at one end thereof and insulated from the frame, a fork comprising a pair of duplicate members pivoted at one end to the frame at the end of the frame remote from said contact member, a contact plate arranged between the members of said fork, said contact plate having one edge thereof projecting beyond the corresponding edge of said fork members, a bracket on that end of the frame adjacent the contact on said frame, a fusible block carried by said bracket, said block having a grooved edge normally receiving the extended edge of said second mentioned contact plate, whereby upon fusing of said block said contacts are engaged 100 one with the other for closing the circuit, and a weight member on said fork remote from the pivoted end of the fork. 105

2. A switch of the character described comprising in combination a pair of complementary members pivoted at one end, a contact plate clamped between said members, a fixed contact plate, supporting means therefor, a fusible element on said supporting means adjacent said fixed contact plate, and said first mentioned plates having one edge thereof engageable with an edge of said fusible element for normally maintaining said contact plates out of engagement one with the other, said fixed contact plate and said fusible 115 element being arranged remote from the pivoted end of said complementary members. 120

In testimony whereof I affix my signature.
AXEL H. PEARSON.
